UNITED STATES PATENT OFFICE.

FREDERICK P. FULLER, OF NEW YORK, AND JOHN J. WALSH, OF
YONKERS, NEW YORK.

GROUND CONNECTION FOR ELECTRIC CONDUCTORS.

SPECIFICATION forming part of Letters Patent No. 758,057, dated April 26, 1904.

Application filed October 16, 1902. Serial No. 127,518. (No model.)

To all whom it may concern:

Be it known that we, **FREDERICK P. FULLER**, residing at New York, county of New York, and **JOHN J. WALSH**, residing at Yonkers, 5 county of Westchester, State of New York, citizens of the United States, have invented certain new and useful Improvements in Ground Connections for Electric Conductors, of which the following is a specification, reference being had to the drawings accompanying and forming a part of the same.

The object of our invention is to provide means for connecting an electric conductor to a pipe, as one of the gas or water pipes of a building, which shall not only be certain and efficient in operation, but also more easily applied and neater in appearance than the unsightly devices heretofore employed.

Our invention is simple and can be manufactured at comparatively small cost. It consists, essentially, of a band adapted to encircle a pipe or other object and a clamping device for securely fastening the band thereto, together with means for attaching the wire or conductor.

Referring now to the drawings, Figure 1 is a plan view showing one of the clamp members swung out of its operative position. Fig. 2 is a side view of Fig. 1 with the clamping device in section. Fig. 3 is a transverse section on line 3 3, Fig. 2, but showing the conductor and band-sleeve in elevation. Fig. 4 is a plan view of a modification, of which Fig. 5 is an end view. Fig. 6 is a further modification.

As will be seen in the various figures of the drawings, a band 1 is provided, preferably of brass or other good conducting material, one end of which is passed through an opening 2 in a plate 3 and fastened in place in any convenient manner, as by bending the same over one side of the plate 3, as shown at 4, Fig. 3. The other end of the band 1 is also passed through the same or a similar opening in the plate 3 and fastened, a tongue 5 being cut out of the band and bent over the side of the plate for that purpose, as shown in Figs. 1, 2, and 3. The plate 3 has a screw-threaded hole at each end in which are flat-ended screws

6 7. On the lower plate 3 is a second plate 50
8, having openings to receive the screws 6
and 7, one or both of the openings preferably
being slotted, as at 9, Fig. 1. The various
parts being arranged as shown in Figs. 2, 3,
and 4, it is obvious that if the screws 6 7 be 55
screwed in against the pipe 10 the band 1 will
be drawn very tightly around the same, while
the flat ends of the screws bearing with the
same firmness will also furnish a good elec-
trical contact. 62

The grinding of the screws on the pipe produces a clean bright surface on each, and both being held very tightly together the connection at these points constitutes, in fact, the principal contact.

We have shown several methods of connecting the conductor to the band. For example, one end of the band may be bent to form a sleeve 11, Figs. 1 and 3, into which the wire or conductor 12 is passed, the end of the same being wrapped tightly around the sleeve, as at 13, where it may be soldered, if desired, and the sleeve itself filled with solder. In Figs. 4 and 5 the sleeve is arranged transversely, so that the wire or conductor enters the same parallel to the pipe 10. A convenient way of forming this transverse sleeve is to employ an independent strip of metal 14, having a loop 15, in which the conductor is secured. The sleeve is fastened to the band 1 in any suitable manner, as by screws. Instead of a sleeve, however, a binding-post construction may be employed, as clearly shown in Fig. 6.

It will thus be seen that our device may be 85 readily applied or removed and that it furnishes a positive connection with the pipe or other object to which it is secured. At the same time it is not unsightly or cumbersome in appearance and may be made as ornamental 90 as desired. It is understood, of course, that the forms shown are typical merely and are not the only embodiments of which our invention is capable.

What we claim is—

1. In a device of the kind described, the combination of a conducting object, a flexible band encircling the same, a clamping device

engaging the ends of the band, and a screw intermediate the clamping device and the conducting object to push the clamping device away from the conducting object to take up 5 the slack in the band and engage both ends of the band more firmly, as set forth.

2. In a device of the kind described, the combination with a band adapted to encircle a conducting object, of a plate through which 10 the ends of the band pass, a second plate on the first, and screws extending through said plates and bearing against the conducting object, as and for the purposes set forth.

3. In a device of the kind described, in com-

bination, a band adapted to encircle a con- 15 ducting object, a sleeve on said band for receiving a wire or conductor, a plate through which the ends of the band pass, a second plate superimposed on said first-mentioned plate, and screws extending through said plates and 20 bearing against the conducting object, as and for the purposes set forth.

F. P. FULLER.
JOHN J. WALSH.
